UNITED STATES PATENT OFFICE.

FRANK C. ROWE, OF MOUNT CLARE, WEST VIRGINIA.

TUNING-COIL AND CONDENSER MOUNTING FOR RADIORECEIVERS.

Application filed April 29, 1924. Serial No. 709,824.

To all whom it may concern:

Be it known that I, FRANK C. ROWE, a citizen of the United States, residing at Mount Clare, in the county of Harrison and State of West Virginia, have invented certain new and useful Improvements in a Tuning-Coil and Condenser Mounting for Radioreceivers, of which the following is a specification.

10 This invention relates to improvements in radio receiving sets, and particularly to a combined coil and condenser mounting therefor.

An object of the invention resides in providing a mounting for the movable and stationary coils of a tuning inductance, in which the movable coils are positioned between pairs of stationary coils at opposite sides thereof, and connected in series with said movable coil, through a plurality of condenser contact points carried by the mounting for the movable coil, and stationary brushes having contact with said plate, the condenser plates acting to eliminate set noises or other local interferences and increase the tuning qualities of the inductances, in addition to providing a convenient means of making contacts between the movable and stationary coils.

30 Another object of the invention resides in providing a combined tuning inductance and condenser mounting, for radio receiving sets, wherein primary and stationary inductance coils are separated into sections connected in series, and in which certain of said sections are carried on a movable mounting element arranged between a pair of stationary mounting elements carrying the stationary portions of the coil, in relative 40 inductive relation, a plurality of contact condenser plates being provided on the movable mounting element arranged on the axis of rotation thereof, and with which contact a plurality of brushes arranged in predetermined relation, for connecting the several coil sections of the primary and secondary in series, and at the same time providing a means for reducing local interference to a minimum, and a tuning condenser being included in the primary circuit, and mounted in the movable mounting element, having a plurality of relatively rotatable plates, which are movable relative to the movable mounting element and independently thereof, for

cooperation with the stationary plates of the condenser, when used for tuning purposes.

A further object of the invention resides in providing a combined tuning inductance and condenser mounting for radio receiving sets, wherein the tuning inductance includes primary and secondary windings, each of which is divided into a plurality of sections, certain of which are mounted on a movable mounting element positioned between a pair of stationary mounting elements so that the rotation of the movable mounting elements for tuning the primary will effect a corresponding tuning action of the secondary simultaneously therewith, in order that the inductive relation of the primary and secondary may be balanced, a plurality of contact condenser plates being mounted on the movable mounting element, at right angles to the axis of movement thereof, with which contacts a plurality of brushes, which are used for interposing the several sections of the primary and secondary windings in circuit, in a predetermined relation, and a variable condenser also arranged in series in the primary circuit, for tuning purposes, having the rotary control shaft, for varying the capacity thereof arranged in axial alignment with the control for rotating the movable mounting element, in order that the controls for the tuning devices of the set may be centralized for convenient operation, and a cooperation in tuning and elimination of set noises.

The invention also comprehends other objects and improvements in the details of construction and arrangement of parts which are more particularly pointed out in the following description and claims, directed to a preferred form of the invention, it being understood however, that variations may be made in this specific construction, without departing from the spirit and scope of the invention as described and claimed.

In the drawing, forming a part of this application:

Figure 1 is a plan view of the invention in assembled relation.

Figure 2 is a sectional view, taken on the line 2-2 of Figure 1.

Figure 3 is a detail sectional view, on an enlarged scale, taken on the line 3-3 of Figure 1.

Figure 4 is another detail enlarged sectional view, taken on the line 4—4 of Figure 1.

Figure 5 is an enlarged detail view of the condenser contact plate, taken on the line 5—5 of Figure 1.

Figure 6 is a wiring diagram, showing the connection between the condenser and the primary and secondary windings.

10 A pair of panels or mounting plates are indicated at 1 and 2 respectively, between the outer ends of which are mounted a pair of stationary tubular coil mountings 3, in axial spaced relation. Each of these mountings 3, are provided with a pair of spaced coil windings 4 and 5 respectively, the winding 4 being the stationary portion of the secondary winding, while the windings 5 are stationary portions of the primary windings. The ends of the coils 5 are electrically connected to screws 6 and 7 respectively, which extend through the panel section 2 and provide a means of mounting the tubes 3, in spaced relation with said panel section, while screws 8 have one end of the coil 4 connected thereto and extend through the panel section 1, for mounting binding posts 9 on the outer ends thereof, adapted for receiving proper connections for interposing this coil in the receiving circuit of the set. The other end portions of the windings 4 are electrically connected with screws 10, which are secured to contact strips 11 mounted on the panel 1, the screws 8 and 10, and strips 11, serving to properly mount the tube section 3, in proper relation with the panel 1, in order to form a unit assembly. A movable coil mounting includes a main tubular member 12 of equal size with respect to the tube 3, and rotatable therein, on an axle extending transversely to the axis of the tubes 3, through the medium of bearing brackets 13, mounted in diametrically opposite sides of the central portion of the tube, which are rotatable on tubular shaft members 14 and 15 respectively, the shaft member 15 having a bearing in the bearing sleeve 16, carried by the panel 2. The main tube 12 is provided with pairs of spaced windings 17 and 18 respectively, the windings 17 being included in the primary circuit, while the windings 18 are secondary windings, included in the corresponding circuit with the secondary windings on the tube 3. A pair of contact condenser plates are indicated at 19 and 20 respectively, mounted between the tube 12 and the panel 1, in spaced concentric relation with the tubular shaft 14 on the screw members 21 and 22 respectively. The screws 21 and 22 are carried by the tube 12 and the screws 21 mount the contact plate or disc 19 in spaced relation thereto, and said plate 19 is formed with openings 23, through which pass the screws 22 which mount the contact plate 20,

in spaced relation with the plate 19 and the panel 1, the plates being electrically insulated from one another in said spaced relation.

Another contact plate is indicated at 24, which is of annular form, formed with a central opening to receive the tubular shaft 15 in spaced relation therein, and which is mounted on screw members 25, in spaced relation with the tube 12 and panel section 2, for rotation with the tube 12. The windings 18 on the main movable tube 12 each have one end electrically connected to the contact plates 19 and 20, through the screws 21 and 22 respectively, while the windings 17 each have one end connected to the contact plate 24 through the screws 25 and the other end connected to the bearing sleeve 16, which is rotatable in the panel 2, and connected to the tube 12 by suitable screw members 26, which extend through the elongated opening formed in the contact plate 24, which bearing sleeve is adapted to form the operating means for receiving a manually operable dial or handle, for operating or rotating the tube 12 in the tuning operation.

A screw member 27 extends through the panel 1 and mounts on the outer face thereof, a binding post 28, and at the inner end a pair of contact arms 29, adapted to straddle the contact disc 19, and provide electrical connection therewith, the binding post 28 receiving the connection of the secondary circuit of a receiving apparatus.

A pair of contact brushes 30 are connected to the panel 1, by a suitable connection, which extends through the contact strips 11, and provide electrical connections between the brushes 30 and the contact strips 11, so that a circuit will be made between the movable and stationary secondary coil windings adapted to connect them in series in the receiving circuit.

Brushes 31, mounted on the panel sections 2 by suitable screws are electrically connected with the screws 6 by strips 32 of suitable metal, the brushes contacting with the disc 24 which provides electrical connection between the primary windings 17 on the tube 12 and the stationary primary windings 5 on the tubes 3, which are placed in the circuit between the aerial and the ground in a manner to be described, the ground connection being preferably made with the screws 7.

A supplemental movable tube is indicated at 33, of a diameter smaller than the main tube 12, and which is positioned within said main tube and rotatably mounted in axial relation therewith, on the tubular shaft 15, at one side and the tubular shaft section 14 at the other side, the shafts 15 and bearing sleeve 16 being in electrical communication for purposes which will presently appear. The supplemental tube 33 is provided with

windings 34, arranged in spaced relation adjacent opposite ends of the tube, one end of each winding being electrically connected to the tubular shaft 15, while the other ends 5 of the windings are connected to the bracket extensions 35, on one end of the tubular shaft sections 14.

A pair of insulating sleeves 36 and 37 respectively, are positioned within the tubular shafts 13 and 14, and rotatably receive rods 38 and 39, the rods 39 having a relatively rotatable extension 40 connected thereto, having bearing in the panel 1 and which forms the mounting in said panel, for the movable tubes 12 and 33 and the remaining structure connected therewith. A coil spring 41 is positioned under compression between an insulating sleeve 42 and a collar 43, on the rod extension 40, for holding said sleeve in bearing contact with the panel 1. The inner end of the rod 39 receives and mounts a bar member 44, the ends of which are attached to the ends of the bracket extensions 35 and through which extend elongated 25 screws 45, which mount a plurality of stationary condenser plates 46 in spaced relation between the bar member 44 and the bar member 47, arranged in spaced relation therewith, and connected at the opposite 30 ends of the screws 45 and supported on the rod 38, in the central portion thereof. The end of the rod 38 rotatably seat in the end portion of the rod portion 39 in a manner clearly shown in Figure 2, and mounts a 35 plurality of movable condenser plates 46 adapted for cooperation with the stationary plate 46, to provide a variable condenser structure within the supplemental tube 33. A collar 48 is adjustably mounted on the rod 40 38 and adapted to contact with the ends of the insulating sleeve 36, for retaining the end of the rod 38 in its bearing relation in the socket formed in the end of the rod 39. The supplemental tube 33 is retained on the 45 end portions of the tubular shafts 15 and 14 respectively, by a suitable nut 49, screw threaded on portions of said shaft, in a manner clearly shown in Figure 2.

The circuit from one side of the windings 50 34 on the tube 33, being connected with the extensions 35 provide an electrical circuit to the stationary condenser plates 46, which is completed through the movable condenser plates 46 and the shafts 38, which connect it 55 to the serial or ground side of the circuit as desired, for interposing the primary winding in series with the variable condenser in the antennae ground circuit of the receiving set.

Upon examining the wiring diagram, in 60 Figure 6, the circuit connections for the several coils on the movable tubes 12 and 33 as well as the stationary tubes 3 may be readily ascertained, from which it will be 65 clear how the unit assembly of variable con-

densers and tuning inductance is used in the radio receiving circuit.

In this construction, it will be seen that by mounting the variable condenser within the tube 33, the adjustment for the movable 70 plates is in axial alignment with the adjustment or means for rotating the tubes 12 and 33 relative to one another and the stationary tube 3, so that the controls or adjusting dials for the several movable parts, may be arranged in axial alignment, and superposed relation in order that a convenient adjustment between the several parts may be effected. The association of the several elements in the manner illustrated, will also 75 increase the inductive relation and amplification of the signals received in the secondary windings of the construction. The contact plates 19, 20 and 24 will not only act as a shield for eliminating internal set noises, 80 but the plates 19 and 20 will also have a condenser action, in cooperation with the inductive winding of the coils, which will be of a substantially permanent character.

The construction above described forms 85 an assembled unit, which is adapted to be mounted on an instrument panel of the receiving set, through the medium of the screws 7, extending through said panel, and receiving suitable nuts for mounting the assembly on the panel. The sleeve 16, tubular shaft 15, and rod 38, extending through an opening in the instrument panel of the set, (not shown), in front of which the sleeves, 90 shaft and rod are adapted to receive the operating dials, through which the operation of the movable coils and the condenser may be effected, and the position of adjustment ascertained.

From this construction, it will be seen that 95 a unit assembly has been provided for the primary and secondary windings, as well as a variable condenser, portions of both the primary and secondary windings being arranged on the movable tube for relative 100 rotation and tuning adjustment with respect to the stationary portions of the winding, in a single operation of one adjustment, while the primary winding has an additional movable coil, adapted for adjustment, 105 relative to both the stationary windings and the movable portions of the secondary, as well as other portions of the primary windings, during the tuning operation of the receiving set, in which it is interposed for 110 effectively tuning the same to receive a desired signal.

What is claimed is:

1. A tuning coil assembly comprising a 115 pair of spaced tubular stationary coil mountings, arranged in axial alignment, a tubular coil mounting rotatably mounted between and on an axis substantially at right angles to the axes of the stationary 120 mountings, and adapted to be positioned in 125 130

- 5 axial alignment with said stationary mountings, a plurality of contact condenser plates carried by the rotatable coil mounting, stationary brushes engaging said plates, primary windings mounted on the movable and stationary coil mounting tubes, and connected in series through said contact condenser plates and brushes respectively, and secondary windings mounted on said movable and stationary tubes respectively, inductively arranged relative to the primary windings and also connected in series through the contact condenser plates and brushes.

10 2. A tuning coil assembly comprising a pair of spaced panel sections, a pair of stationary tubes mounted on and between said channel sections in spaced relation, a main rotatable tube mounted between said stationary tubes and the panels, having means for rotatably supporting said tube sections on an axis at right angles to said panels, a plurality of contact plates mounted in spaced relation between the main tube and the panels, stationary contact brushes carried by the panels engaging said plates, said main tube being provided with a plurality of coil windings arranged in spaced relation and electrically connected with said contact plates, said stationary tubes being provided with pairs of coil windings, certain of the coils on the main tube and stationary tube being connected in series through the contact plates and brushes, to form a primary circuit, while the remaining windings are adapted for connection through said plates and brushes, in series, to form secondary windings, a sleeve member mounted in said main tube and rotatably mounted in one of said panels, in axial relation with the axis of rotation of said main tube, adapted for receiving means for the adjustment of the main tube for tuning purposes, a supplemental tube having a sleeve extension therefrom extending through the sleeve on the main tube and rotatable therein, insulating means being interposed between the tubular extensions, said supplemental tube being adapted for rotation relative to the main tube, through the tubular extension thereon, a variable condenser mounted in said supplemental tube, a shaft extending through the tubular shaft of the supplemental tube and insulated therefrom, for varying the capacity of said variable condenser, centralizing the control for the movable tubes and the variable condenser, in axial arrangement, said supplemental tube having coil windings thereon, connected in series with the coil windings of the main tube and the variable condenser, adapted to form the primary circuit therewith.

15 3. A tuning coil and condenser assembly comprising a pair of spaced panel sections, a pair of stationary tubes mounted on and between said panel sections in spaced relation, a main rotatable tube mounted between said stationary tube and the panels, means for rotatably supporting said main
